HEN'S NEST

Walter F. Leibenguth, Mill River, Mass.

Application November 11, 1936, Serial No. 110,379

1 Claim. (Cl. 119—45)

This invention relates to hens' nests and has for its object to provide a nest which can be readily cleaned; which can be used singly or in multiple with common bottom and top; which can be turned in a reverse direction when occasion demands without moving the nest bedding or hen, and which can be manufactured cheaply, and inexpensively shipped.

Other objects of the invention will appear as 10 the following description of a preferred and practical embodiment thereof proceeds.

In the drawing throughout the several figures of which the same characters of reference have been employed to designate identical parts:

15 Figure 1 represents a multiple arrangement of hens' nests embodying the principle of my invention;

Figure 2 is a side sectional view through a hen's nest showing the lower portion of a superposed nest;

Figure 3 is a cross section taken along the line 3—3 of Figure 2; and

Figure 4 shows a plurality of the side wall blanks nested for shipping.

25 Referring now in detail to the several figures, the numeral 1 represents in general the side wall structure of the hen's nest which is of bendable sheet material and preferably of metal although it is to be understood that the invention is not 30 restricted to the use of metal. The side wall structure is open at the top and bottom and provided with a lateral entrance opening 2. This opening may be of any desired shape. Preferably it is a continuous arc 3 at the top and sides and 35 has a flat circumferential edge 4 at the bottom. Although the edges of the sheet material may be left unfinished at the top and bottom and around the entrance opening, it is preferred to bend the material over as indicated at 5 and 6 forming a 40 close bead.

While the side wall structure may be set up in cylindrical form at the place of manufacture, it will facilitate the convenience and reduces the cost of shipping if the sheet material is formed 45 at the factory with the elements of an open seam, namely, the oppositely turned flanges 7 and 8, see Figure 4. When the side wall structure reaches its place of destination, the turned edges 7 and 8 are interlocked and mashed together 50 forming a closed seam as indicated at 9 in Figure 3.

The nest is composed by placing one or more of the side wall structures 1 upon a flat board or other similar supporting member 10. No fastening means are used, the side wall structure

resting freely upon the bottom member. A similar board 11 may be rested upon one or more side wall structures functioning as a top for them and as a bottom for a superposed nest or row of nests.

If full benefit is to be derived from the advantages of the nest, the top board is preferably suspended a slight distance above the underlying row of nests by means such as the bracket 12. This not only provides ventilation for the nests, 10 but makes it possible to clean or renovate the nests in any row without disturbing the other rows. The top board 13 of a tier may be slanted if desired to shed rain.

It will be observed that the lower edge 4 of 15 the entrance openings is spaced some distance above the bottom edge of the side wall structure providing a laterally enclosed space to receive the nest bedding 14. When it is desired to clean the nests or renew the bedding, the side wall structures are slidably removed from the supporting bottom board 10. The board can then be scraped with a hoe or brushed or in any other desired manner cleaned or disinfected. The side wall structures can then be replaced and new bedding 20 supplied.

If, and as is preferred, the side wall structures are made of metal or other non-absorbent material, they can be immersed in a tub of scalding water or disinfectant liquid for the purpose of 25 inhibiting or exterminating vermin. If of metal they can even be subjected to fire without damage.

One of the advantages of a cylindrical side wall structure is that when it is desired to make a 30 hen stay on her nest for brooding purposes, any one of the nests upon which a broody hen may be found, may be rotated so as to bring the entrance to the rear as for example against the 35 wall of a hen house or barn, without rotating the bedding or disturbing the hen. After a day or two, or when the hen has acquired the urge to remain, the side wall structure may be again rotated to a position in which the hen may leave her nest.

It will be understood from the above description that I have provided a hen's nest having all the advantages as above described and without corners or crevices which would make it difficult to keep clean and free from vermin and 40 while I believe that the form of my invention as illustrated and described is simple and thoroughly practical, it will be understood that it is within the scope of the invention to vary the details of 45 construction and arrangement and still be with- 50 55

in the protection accorded by the appended claim.

What I claim is:

5 Nest colony including a bottom board and a plurality of open bottomed cylindrical side wall structures, freely set on said board, each having an entrance above the lower edge of said side wall structure providing a laterally enclosed space below said entrance for nest bedding, and

a top board slightly spaced from said side wall structures serving as a closure for the upper end of said structures, and adapted to serve as a bottom for a superposed row of nests, said side wall structures being rotatable upon said bottom board to reverse position without rotating the bedding which rests upon said bottom board. 5
